UNITED STATES PATENT OFFICE.

NORMAN C. BASSETT, OF BOSTON, MASSACHUSETTS, ASSIGNOR TO THE GENERAL ELECTRIC COMPANY, OF NEW YORK.

ELECTRIC SWITCH.

SPECIFICATION forming part of Letters Patent No. 677,923, dated July 9, 1901.

Application filed April 28, 1900. Serial No. 14,681. (No model.)

To all whom it may concern:

Be it known that I, NORMAN C. BASSETT, a citizen of the United States, residing at Boston, county of Suffolk, State of Massachusetts, have invented certain new and useful Improvements in Electric Switches, (Case No. 1,043,) of which the following is a specification.

My present invention relates to electric switches, and has for its object to provide a simple and effective means for maintaining a switch-lever normally in a definite zero or off position and for exerting a force tending to return it to said position whenever it is moved.

My invention is particularly applicable to that type of controlling-switch for motor-circuits in which a means is provided for locking the switch-lever in its operative position, the said locking means being controlled by the current flowing in the motor-circuit, so that whenever the said current fails the switch-lever will be released.

In the drawings annexed to this specification, Figure 1 shows a plan view of my invention as applied to a reversing-rheostat, and Fig. 2 is a view in side elevation.

Referring to the drawings, B indicates the box, and C the connection-board, of an ordinary rheostat. On the connection-board is mounted the switch-lever L, pivoted at the point O and carrying the brushes *abcd*, which engage with the segments or contacts *efgh* and the contacts *i* and *i'* to make the required circuit connections. D indicates the binding-posts, from which circuits lead to the source of current-supply and to the motor-terminals. The switch-lever L is provided at its ends with guides G, having curved ways inclosing straps s, each fastened at one end of the guide to the pin k and depending therefrom, the straps constituting a convenient means for manipulating the switch-lever when the rheostat itself is mounted in an inaccessible position—

as, for example, near the ceiling of a room. In order to maintain the switch-lever L normally in its off position and in order to return it to such position whenever it is desired to open the motor-circuit, two springs S and S' are provided. These springs are rigidly fastened at their lower ends to plugs o and

o', pivoted on the pins l and m, and at their other ends are fastened to nuts which engage with threaded portions on the rods r and r'. These rods are provided at their upper ends with enlarged portions and are of such a length that when the lever L is in its zero position the enlarged portions engage countersunk openings in a suitable support n, arranged opposite the pivot of the lever, while the lower ends engage, respectively, the upper surfaces of the blocks *o* and *o'*. By turning the rods into the nuts at the upper ends of the springs the springs may be given any desired initial tension. As the lever L is moved in one direction or the other the tension of the spring on one side is increased, while on the other side the rod plays through the opening in the support n. For example, when the lever L is moved in right-handed rotation the tension of the spring S' will be increased as the block *o'* swings downward around the pivot O, while on the other side as the block *o* swings upward around the pivot O the rod r will play through the aperture in the support n. Under these conditions the spring S, though maintained under its initial tension by the engagement of the lower end of the rod r with the block *o*, is entirely inoperative, while the spring S' is under an increased tension and tends to return the lever to its zero position. If after having been so moved the switch-lever is released, the spring S' will throw the lever back to its zero position, and when it has reached such position the head of the rod r will again engage its countersunk aperture and the spring S will be brought into action to prevent the lever from swinging by the center. The operation when the lever is moved in the reverse direction is of course similar. The initial tension given to the springs S and S' determines both the force with which the lever will be thrown back to its zero position and the force opposing the movement of the lever past its zero position when it is thrown back. By proper adjustment of the tension of the springs, therefore, the lever may be given any desired impulse within the capacity of the springs and may be prevented from vibrating when it comes to its zero position.

It is evident that it is not necessary that the upper ends of the springs S and S' shall be supported from a single member. Instead of supporting these springs, therefore, from 5 the support n, a separate support may be provided, if desired, for each. In order that the switch-lever may be maintained in its full-on position when turned either to the right or to the left, an electromagnet M is provided having 10 polar extensions on each side at the top and bottom, the support n constituting one of the poles of the magnet and the part p the other. The lever L is provided at each end on its upper side with armatures A and A', 15 adapted to engage the polar projections of the said magnet. This magnet is supplied with current in series with the motor-circuit controlled by the said switch, as is customary in motor-controlling switches, so that whenever 20 the current-supply fails for any reason the switch-lever will be released and returned to its zero position.

The operation of my device is as follows: When it is desired to start the motor in one 25 direction, the lever L is moved by means of one of the straps s—as, for example, the one on the left—until the brushes a and b come into contact with their corresponding segments f and h and brushes c and d come into 30 contact with the segment g and with one of the contacts i. As the switch-lever is still farther moved the brush d engages the successive contacts i, gradually cutting out the 35 resistance of the rheostat in a manner well understood, until, finally, when the switch-lever has reached its full-on position the armature A' comes into contact with the poles of the electromagnet M, and the switch-lever is held thereby so long as the current flows 40 in the motor-circuit. Whenever the current fails in the motor-circuit, the armature A' will be released and the switch-lever returned to its zero position in the manner already described, and also whenever it is necessary to 45 stop the motor the armature A' may be withdrawn from engagement with the polar projections of the magnet M by means of the strap s on the right. If it is desired to cause the motor to rotate in the opposite direction,

the lever L will be operated by the straps on the right to bring the brushes a and b into engagement with the segments e and g and the brushes c and d into engagement with the segment h and the contacts i', and when the lever has reached its full-on position on this side it will be held, as before, by means of the armature A engaging the polar projections of the magnet M.

While I have shown my invention as applied to a reversing-rheostat, it is evident that it is not limited thereto, but may be used in connection with any switch member whenever it is desired to maintain such member in a definite off position unless it is not positively held in an operative position, and although I have shown an electromagnetic means for maintaining the switch-lever in either of its operative positions it is evident that I am not limited thereto, but may use any suitable locking means for maintaining the lever in such positions.

What I claim as new, and desire to secure by Letters Patent of the United States, is—

1. In combination, a pivoted switch member and a plurality of spring devices for returning said member to its "off" position from either direction, each of said devices being so mounted that it is inoperative in one direction of movement of the switch member, and each comprising two members normally maintained in engagement by a spring connection.

2. In combination, a pivoted switch-lever, blocks rotatably mounted on either side of the pivot of said lever, a plurality of fixed supports, rods having at their upper ends enlarged portions normally engaging said supports and having their lower ends normally in engagement with said blocks, and springs, each fastened at one end to one of said blocks and at the other end to a point on one of said rods.

In witness whereof I have hereunto set my hand this 25th day of April, 1900.

NORMAN C. BASSETT.
